By E. B. Whitmore, Atty.

UNITED STATES PATENT OFFICE.

JAMES McARTHUR, OF ROCHESTER, NEW YORK.

SASH-BALANCE.

SPECIFICATION forming part of Letters Patent No. 354,162, dated December 14, 1886.

Application filed October 5, 1886. Serial No. 215,395. (No model.)

To all whom it may concern:

Be it known that I, JAMES McARTHUR, of Rochester, in the county of Monroe and State of New York, have invented a new and useful

5 Improvement in a Device for Suspending Sash, which improvement is fully set forth in the following specification and shown in the accompanying drawings.

The object of my invention is to produce a 10 compact device for holding or suspending a window-sash to take the place of the weights and cords commonly used for the purpose, said device being fully described hereinbelow, and more particularly pointed out in the claims.

15 Referring to the drawings, Figure 1 is a side sectional elevation of the device, showing the parts in place, the frame of the window, a part of the frame of the sash-suspender, and the spring-drum being vertically sectioned, as on 20 the dotted line *x* in Fig. 2, and viewed as indicated by the arrow pointed thereon a portion of the sash being similarly sectioned as on the dotted line *y* to show the staple embedded therein; Fig. 2, an elevation of the device 25 vice viewed as seen by arrow *z* in Fig. 1; Fig. 3, a view of the same in the opposite direction; Fig. 4, a view of the device indicated by arrow *x'* in Fig. 1, the minor springs being omitted; Fig. 5, drawn to a much smaller scale, an elevation of a portion of a window with its casing, sash, &c., the frame being vertically sectioned 30 to show the suspending devices for the sash at either side thereof, the figure being drawn to show the relative position of the parts; and Fig. 6, a view of the shaft of the spring-drum seen in the direction in which Fig. 3 is seen.

Referring to the parts, A is the frame of the window of any suitable style or kind; B, the sash thereof, and C the plate of glass in the 40 sash.

D is the frame of the device for suspending the sash, consisting of a plate, *a*, and side pieces, *b*.

45 *c* is a cylinder or drum inclosing a flat coiled spring, *d*, the action of which, with its mate at the opposite side of the window, suspends the sash.

50 *e* is a bar or shaft passing through the drum, corresponding to the axis thereof, having its projecting ends made rectangular, and resting rigidly in corresponding notches, *f*, formed in the side pieces of the frame, by means of which

it is prevented from turning, while the drum may turn freely thereon.

g is a band or suspender for the sash, having 55 one end secured to the convex edge of the drum and wound therearound, passing thence through an opening, *h*, in the plate *a*, and secured at its other end to a staple or holder, *h*, inserted in the sash, as shown. 60

i is a friction-strap, constituting a brake or 65 detent for the sash, acting upon the suspender, being substantially semicircular in form and held in position to bear upon the outer coil of said suspender as it lies upon the drum. 70 The strap or brake *i* is held at one end by a transverse pin, *l*, rigid with the frame, and at the other end is bent outward and pierced to receive a stud, *n*, secured to the plate *a* in a position at right angles therewith. At its 75 free end the stud is threaded and provided with a screw-nut, *o*, between which and the brake *i* is placed a spiral spring, *p*, which latter tends to hold the brake down upon the suspender *g*. 75

Between the brake and the head of the stud or frame a weak spiral spring, *r*, is placed upon the stud, which tends to hold said brake at all times against the spring *p*. These two oppositely-acting springs serve to hold the brake 80 steady and prevent it vibrating or clattering when the suspender rubs against it as the drum is turned. By turning the screw-nut *o* toward or from the spring *p* the brake will be caused to bear heavier or lighter upon the suspender *g*. 85

The spring *d* is coiled in the drum in such a manner that it tends to turn the latter in the direction indicated by the arrow *t*—that is to say, in a direction to pull upward upon the sash. The holder *h* is preferably inclined upward in the sash, as shown, to better hold itself in place therein and prevent being pulled out by the suspender. 90

Regarding the upper sash, it will be seen that when it is well down and the suspender 95 nearly unwound from the drum there is little or no contact between said suspender and the brake; but when the sash is raised and approaches its normal place the suspender thickens upon the drum from the added coils under 100 the brake, which causes the latter to bear more firmly thereagainst, and to so offer increased resistance to the upward-moving sash, thus tending to prevent the latter being brought

violently against the frame at the top. On account of the spring *p* and the elasticity of the brake itself the latter always bears upon the suspender to control the movement of the 5 sash with a yielding pressure, adding to the smoothness of the working of the device.

The suspending devices are let into openings *E*, formed in the opposing sides of the window-frame, so that the outer surfaces of 10 the plates *a* shall be even with the adjacent surfaces of the frame in the places usually occupied by the cord-pulleys where counter-weights are used, the devices being held in place by common screws, at *s*, in the usual 15 manner.

The coiled spring *d* is secured at one end to the shaft *e* and at the other to the concave surface of the drum, so that when the sash is pulled down the spring is wound up or strained.

20 Springs, heavy or light, are to be used according to the weight of the sash to be suspended in each given case.

What I claim as my invention is—

1. In a sash-suspending device, a frame, a 25 rotating spring-drum with contained spring held by said frame, and suspending-band for the sash, secured to the latter and to said drum, in combination with a semicircular tension-band secured to said frame substantially concentric with said drum, bearing upon said 30 suspending-band to act as a tension therefor,

said tension-band acting upon said suspending-band only when the connected sash is approaching its uppermost position or increasing its action on said suspending-band as said 35 sash rises, substantially as described.

2. In a sash-suspending device, a frame, a rotating spring-drum with contained spring held by said frame, and suspending-band for the sash secured to the latter and to said drum, 40 in combination with a semicircular tension-band secured to said frame substantially concentric with said drum, bearing upon said suspending-band to act as a tension therefor, 45 said tension-band being held against said suspending-band by a spring, *p*, acting upon its free end to press said suspending-band more firmly as said sash moves upward, substantially as described.

3. In a device for suspending a window-sash, 50 a frame, a rotating spring drum or holder with contained spring, and band or suspender for the sash, secured to the latter and to said drum, a brake or retarder for said sash, in combination with springs *p* and *r* for said retarder, 55 and threaded stud and screw-nut, substantially as and for the purpose specified.

JAMES MCARTHUR.
